United States Patent Office

Des. 189,812
Patented Feb. 28, 1961

189,812

TRACTOR

William F. H. Purcell, Pasadena, and James M. Conner,
Glendale, Calif., assignors to Deere & Company, Mo-
line, Ill., a corporation of Delaware

Filed July 13, 1960, Ser. No. 61,351

Term of patent 14 years

(Cl. D14—3)

FIG. 1

FIG. 2

FIG. 3

FIG. 4

FIG. 5

FIG. 6

FIG. 7

Fig. 1 is a three-quarter perspective as seen from the left front of the tractor embodying our new design.

Fig. 2 is a three-quarter perspective as seen from the right front thereof.

Fig. 3 is a perspective showing the tractor largely from the left side thereof.

Fig. 4 is a three-quarter perspective as seen from the right rear thereof.

Fig. 5 is a perspective as seen largely from the front of the tractor.

Fig. 6 is a perspective as seen largely from the rear and top of the tractor.

Fig. 7 is a perspective as seen from above the tractor. The essential features of our design reside in those portions shown in full lines.

We claim:

The ornamental design for a tractor, substantially as shown and described.
